UNITED STATES PATENT OFFICE.

JULIUS NELSON CAYO, OF GARY, INDIANA.

VENDING-MACHINE.

1,119,683.

Specification of Letters Patent.

Patented Dec. 1, 1914.

Application filed November 11, 1913. Serial No. 800,363.

To all whom it may concern:

Be it known that I, JULIUS N. CAYO, a citizen of the United States, residing at Gary, in the county of Lake and State of Indiana, have invented new and useful Improvements in Vending-Machines, of which the following is a specification.

This invention relates to improvements in vending machines and has particular application to a coin controlled vending machine for dispensing cigars when the proper coin has been deposited in the machine. It will be understood, however, that my invention in its useful application is not limited to the dispensing of any particular commodity, as various articles may be vended.

In carrying out the present invention, it is my purpose to provide a vending machine by means of which, when the proper coin has been inserted in the machine, cigars will be dispensed singly. It is also my purpose to provide a machine of the class described which will be constructed in such manner that the articles will be vended singly and the remaining articles automatically held in the machine and wherein congestion will be eliminated and the commodities discharged from the machine successively in accordance with the insertions of coins in the machine. Furthermore, I aim to provide a coin controlled vending machine which will be comparatively simple in construction and efficient and positive in operation and which may be installed and maintained at a minimum cost.

With the above and other objects in view, the invention consists in the construction, combination and arrangement of parts hereinafter set forth in and falling within the scope of the claims.

In the accompanying drawings; Figure 1 is a view in front elevation of a machine constructed in accordance with my present invention. Fig. 2 is a vertical sectional view through the same, parts being shown in elevation. Fig. 3 is an enlarged front elevation of the mechanism of the machine, the casing being removed. Fig. 4 is a top plan view of the same. Fig. 5 is a sectional view on the line 5—5 of Fig. 4 looking in the direction of the arrow. Fig. 6 is a sectional view on the line 6—6 of Fig. 4 showing the feeding and distributing devices. Fig. 7 is an enlarged sectional view of a portion of the machine showing the manner in which the coin operates to render the mecha-

nism of the machine operative. Fig. 8 is a vertical sectional view through an article holder.

In the present instance, I have shown a duplex vending machine capable of vending cigars of various prices, the duplex apparatus being controlled from a single handle. It will be understood, however, that the machine may embody any number of vending units and each unit may be of any desired capacity, all of such units being controlled by a single operating handle, the units being so correlated and arranged that the insertion of a coin of a particular denomination in the respective slot or chute will render that particular unit only operative independently of the other units.

Referring now to the accompanying drawings in detail, the numeral 1 indicates the casing or housing of a machine which is constructed of any suitable material and is preferably provided with a front wall of glass, the said casing being formed in such manner as to nicely accommodate the various mechanisms of each unit of the machine.

In the present instance, the machine embodies two vending units, each including standards 2, 2 extending upwardly from and suitably secured to the base of the casing adjacent to the front and rear edges thereof, the standards being appropriately spaced apart and of different heights, the rear standards being taller than the front standards. Suitably connected to the upper end of each standard 2 or formed integral therewith as desired is a yoke 3 having the free limbs of the arms thereof extended outwardly as at 4 and thence projected upwardly as at 5, the outwardly and upwardly extending portions of the yoke receiving a trough 6 inclined downwardly toward the front of the machine, incident to the difference in height of the standards supporting the yokes. The feeding mechanism of each unit, comprises, in the present instance, drums 7, 7 journaled in the respective yokes 3, 3 adjacent to the opposite ends of the lower wall of the trough 6, and an endless band 8 of some suitable material trained over said drums and having the upper reach thereof resting upon the upper surface of the lower wall of the trough, a ratchet wheel 9 being suitably fastened to one end of the axle of the forward drum so as to impart movement to the feeding device in a manner which will presently appear. Sur-

mounting the trough 6 of each unit at the rear end thereof is a container 10 composed, in this embodiment of my invention, of a substantially rectangular receptacle divided into compartments 11 by means of vertically extending partitions 12, the compartments being of such dimensions as to permit the article to be vended, cigars, in the present instance, to lie horizontally therein one upon the other. Each compartment preferably has the lower end thereof equipped with a swinging check or gate 13 pivoted to the lower edge of the wall of the respective compartment and adapted to hold the articles within such compartment against discharge, while the lower edges of the side walls of each container are provided with downwardly extending ears 14, 14 adapted to contact with the adjacent side walls of the trough 6 and having openings therein aligning with openings in the side walls of the trough and the upwardly projected portions of the rear yoke 3 to receive pivot pins 15, 15 whereby the article container is secured to and capable of swinging movement upon the trough of the respective unit, the forward lower edges of the side walls of the container being provided with downturned lugs 16, 16 designed to embrace the side walls of the trough so as to maintain the container in proper position for feeding the cigars therefrom.

In the present instance, standards 17, 17, one for each unit, extend upwardly from the rear edge of the base of the casing or housing 1 immediately behind the respective rear standard 3 and each of said standards 17 terminates in a yoke 18 having journaled in the opposite limbs thereof a drum 19 having one end of a tape 20, or some other suitable flexible element connected thereto and adapted to be wrapped or wound thereabout, said tape being trained over a roller 21 journaled in the yoke 18 above the drum 19. The free end of this tape 20 is connected to the forward edge of a regulating device composed of a block 22 provided on its lower surface at the opposite edges thereof with runners 23 adapted to slide upon the lower wall of the trough 6 at the opposite sides of the band 8, the tape 20 being passed beneath the block between the runners thereon while the block is interposed between the lower end of the container and the trough and controls the gates or checks 13, the shaft of the drum 19 being provided with a ratchet wheel 24 whereby the drum may rotate to slide the block 22 within the trough and toward the rear end thereof to release the gates 13 controlling the compartments 11 of the respective container successively and at proper intervals.

Mounted at the lower end of the trough 6 of each unit is a separator composed, in the present embodiment of my invention, of

arms 25, 25 each pivoted to one limb of the yoke 3 carried by the forward standard 2 adjacent to the outwardly extended portion of the respective limb and provided with an upwardly extending lug 26 disposed within the trough and having the edge contiguous the top edge of the arm concaved to form a seat 27 cooperating with the seat formed by the lug on the other arm to provide a cradle. The forward extremities of the arms 25, 25 of the separator are each bifurcated to provide a relatively long downwardly extending finger 28 and a short finger 29 disposed above the long finger. Suitably secured to the base of the casing or housing 1 in advance of the forward standard 2 of the respective dispensing unit is an inverted U-shaped yoke 30 carrying on its interconnecting portion an upwardly extending sleeve 31 in which is slidably disposed a rod 32 carrying at its upper end a distributor composed in this instance of a plate 33 having the forward edge thereof slotted as at 34, 34 to pivotally receive cradle forming members 35, 35 suitably spaced apart and formed with upwardly extending fingers 36, rearward extensions 37 disposed in a plane at right angles to that of the fingers and forwardly projecting lugs 38. The contiguous edges 35 of the fingers 36 and the rearward extensions 37 are concaved to form a cradle or seat while the free extremity of each rearward extension is apertured to receive one end of a coiled contractile spring 39 having the free end thereof secured to a downwardly extending strip 40 secured to the under surface of the plate 33 of the distributor, the springs 39 acting to hold the fingers 36 normally vertically. Upstanding from the base of the casing or housing 1 immediately in advance of the inverted U-shaped yoke 30 is a standard 41 carrying at its upper extremity a horizontal pin 42 disposed in the path of movement of the lugs 38 on the cradle forming members 35 so that in the upward movement of the distributor under the action of the rod 32 within the sleeve 31, the cradle forming members will be swung about their pivots and against the action of the springs 39. In order that the separator and distributor may be moved simultaneously, the opposite ends of the plate 33 of the distributor are disposed between the fingers 28 and 29 of the arms 25, 25, while the pins 43, 43 extend outwardly of the strips 40 beneath the relatively long arms 28. Contractile springs 44, 44 each have one end secured to one limb of the forward yoke 3 and the opposite end secured to the rear extremity of the respective arm 25 and act to swing the arms 25, 25 about their pivotal connection.

In the present instance, the operating mechanism of each dispensing unit includes

a bell crank lever 45 having one arm 46 pivoted adjacent to its point of connection with the opposite arm 47 within a bracket 48 secured to the base of the casing or housing 5 of the machine adjacent to the forward edge thereof and in advance of the standard 41, the free end of said arm 46 being connected through the medium of a link 49 with the rod 32, while the arm 47 of the bell crank lever is offset from the arm 46 as at 50 and has pivotally connected to the free end thereof one extremity of a rack bar 51 disposed above and adapted to engage with the teeth of the ratchet wheel 9 on the shaft of the drum 7 carried by the yoke on the forward standard 2. Pivotally connected to the free end of the rack bar 51 is one extremity of a link 52 having the free end pivotally connected to a lever 53, the latter being fulcrumed between its ends upon the standard 17 and carrying a dog 54 spring pressed into engagement with the teeth of the ratchet wheel 24 on the shaft of the drum 19, a second dog 55 being secured to 25 the standard and engaging the teeth of the ratchet wheel to prevent backward rotation thereof. From this construction, it will be seen that as the bell crank lever 45 is swung about its pivotal connection with the bracket 48 in a forward direction, the rack bar 51 will rotate the respective drum 7 to advance the endless band of the feeding mechanism, while the link 52 will impart movement to the lever 53 to rotate the drum 19 and so 30 slide the block 22 rearwardly within the trough 6. Simultaneous with this operation, the rod 32 will be moved upwardly within the sleeve 31 thereby elevating the distributor so that the latter will carry the cigar 35 contained in the cradle forming members 40 thereof upwardly.

In the upward movement of the cradle forming members of the distributor, the lugs 38 on such members engage the pin 42 45 whereby the cradle forming members are swung about their pivotal connection with the plate 33 to dispose the fingers 36 thereof in a position at right angles to the normal thereby discharging the cigar. The separator, being under the influence of the distributor is also actuated in the operation of the distributor so that the lugs 26 on the arms 25 thereof are moved out of the trough 6 and the path of the cigars on the endless 50 band of the feeding mechanism. As the lugs 26 move downwardly, the forward portions of the arms 25 swing upwardly and thereby prevent the cigars from moving out of the trough, while the contiguous edges of 55 the lugs 26 and the arm 25 forming the seats 27 receive the adjacent cigar and throw the latter into the cradle formed by the cradle forming members 35, 35 of the distributor. A spring 56 has one end connected to the base of the casing and the opposite

end fastened to the rack bar 51 so as to insure engagement between the teeth of the rack bar and the ratchet wheel 9 in the forward movement of the bar under the action of the bell crank lever.

The movement of the block 22 is so timed with that gate or check 13 controlling each compartment 11 of the article container is permitted to open as soon as the forward compartment has been emptied. Thus, the 75 compartments are opened successively or one after the other in accordance with the discharge of the cigars thereby obviating congestion in the feeding and distributing mechanisms.

The various mechanisms heretofore described are coin controlled so that the articles dispensed by the machine will be vended only when the proper coin has been deposited within the particular dispensing 85 unit, this coin controlled mechanism is common to both units of the machine and comprises, in the present instance, a member 57 in the form of a rectangular plate composed of two longitudinal sections 58, 58 90 fastened together through the medium of bolts 59 and formed with vertical longitudinal slots 60, 60 spaced apart and opening onto the side edges of the member. This rectangular member 57 at its lower 95 end is provided with laterally extending pivot studs 61, 61 journaled in bearings 62, 62 suitably fastened to the base of the casing or housing between the dispensing units of the machine. A coiled contractile spring 100 63 has one end fastened to an upright 64 secured to the base of the casing adjacent to the rear edge thereof and the opposite end fastened to the member 57, while a shaft 65 is journaled in suitable bearings carried by 105 the base of the casing and formed at one end with a crank arm 66 disposed between the units of the machine and connected by means of a link 67 with the member 57 to swing the latter about its horizontal pivot, 110 the free end of the shaft 65 extending outwardly of one of the side walls of the casing or housing 1 and is equipped with a handle 68. Connected to the free end of the arm 47 of the bell crank lever 45 of 115 each unit is a rod 69 passed through an opening 70 in one wall of the respective slot 60 in the member 57, while the opposite wall of such slot is formed with a relatively large opening 71 alining axially with the 120 opening 70 so that when the operating handle 68 is manipulated before placing a coin in the machine, the member 57 may swing relatively to the rods 69, 69 without influencing the operating mechanism of the various units. The free ends of the rods 69, 69 are preferably upset so as to abut the walls of the openings 70 in the normal condition of the coin controlled mechanism. Immediately below each opening 71 a re- 125

taining pin 72 is passed through the wall of the respective slot 60 and both pins are connected to each other by means of a strip 73 acted upon by a leaf spring 74 to hold the pins projected into the slots. Springs 75, 75 each have one end connected to the strip 73 and the opposite end fastened to the upright 64 so that when the member 57 is moved forwardly under the action of the operating handle, the pins will be withdrawn from the slots 60, 60 in the member 57, a suitable stop being provided to limit the outward movement of the pins so as to avoid displacement thereof, such stops comprising a metallic strip 76 fastened to the member 57 and provided with upwardly projecting arms 77 terminating in offset fingers 78 spaced apart from the adjacent wall of the member 57 to permit the pins 72 to be retracted from the slots.

Each dispensing unit of the machine is provided with a coin chute 79 which, in the present instance, is suitably fastened to the container 10 of the respective unit. These coin chutes are disposed between the units and the lower end of each terminates immediately above the member 57 so that the chutes will align with the slots 60, 60 when the member 57 is in normal position, the upper extremities of the coin chutes extending outwardly of the casing 1 so that the coins may be inserted therein. The coin chute 79 of one unit and the respective slot 60 in the member 57 alining therewith are designed to receive coins of one denomination for instance, "five cents" while the other chute and the remaining slot of the member 57 alining therewith are designed for the purpose of receiving coins of another denomination for example, "ten cent pieces." When a coin is deposited in the respective chute such coin travels downwardly within the chute and drops into the respective slot 60 in the member 57 and is arrested by the respective retaining pin 72 and held in front of the relatively large opening 71 in the wall of the slot, the marginal edges of the coin engaging the wall of such opening, the opening for this purpose being of a diameter less than that of the coin. When the coin is in this position, a fixed connection is established between the member 57 and the respective rod 69 whereby in the movement of the member 57 under the action of the operating handle 58, the rod will travel forwardly and so actuate the respective bell crank lever 45 to cause the operation of the operating mechanism of the particular unit as hereinbefore described, the spring 63 returning the member 57 to normal position upon the release of the operating handle.

In order to close the coin chute 79 of each dispensing unit when the container is empty

so as to notify purchasers of the condition of the machine, any suitable means may be employed. In the present instance, this coin chute closing means is connected with one arm of a bell crank lever 91 pivoted as at 92 to the side wall of the particular container and secured to the free arm of the bell crank lever is one end of a cord 98 or other flexible element having the opposite end thereof fastened to and adapted to be wrapped about a spool 94 surrounding the shaft of the drum 19 and connected to the ratchet wheel 24 of such drum. Thus, as the drum 19 is rotated from the operating mechanism of the particular dispensing unit to move the block 22 rearwardly, the cord 93 will be wrapped about the spool 94 and so operate the chute closing means in a gradual manner. A contractile spring 95 has one end connected to the container of each unit and the opposite end fastened to the bell crank lever to hold the latter in normal position.

From the foregoing description taken in connection with the accompanying drawings, the construction, mode of operation and manner of employing my invention will be readily apparent.

While I have herein shown and described one preferred form of my invention by way of illustration, I desire it to be understood that I do not limit or confine myself to the precise details of construction herein described and delineated, as modification and variation may be made within the scope of the claims and without departing from the spirit of the invention.

I claim:

1. In a vending machine, an article receptacle composed of a plurality of compartments each having an outlet, a block controlling the outlets of the compartments of said receptacle, a feeder adapted to feed the articles from said receptacle, a distributor adapted to have communication with said feeder, and means for operating said feeder and distributor simultaneously.

2. In a vending machine, an article receptacle divided into a plurality of compartments each having an outlet, a gate controlling the discharge of the articles from each compartment, a block adapted for sliding movement and designed to open said gates successively, a feeder adapted to feed the articles from said receptacle, a distributor adapted to have communication with said feeder, and means for operating said block, feeder and distributor.

3. In a vending machine, an article receptacle having an outlet, a trough communicating with the outlet of said receptacle, a block mounted within said trough beneath the receptacle and controlling the outlet thereof and adapted for sliding movement, a feeder comprising a pair of drums,

an endless belt trained over said drums and having the upper reach thereof disposed within said trough, means for operating said drums, and means for operating said block.

4. In a vending machine, an article receptacle having an outlet, a trough communicating with the outlet of said receptacle, a block mounted within said trough beneath the receptacle and controlling the outlet thereof and adapted for sliding movement, a feeder comprising a pair of drums, an endless belt trained over said drums and having the upper reach thereof disposed within said trough, means for operating said drums, means for operating said block, a distributor adapted to have communication with said feeder and comprising a plate, and cradle members pivoted upon said plate.

5. In a vending machine, an article receptacle, a feeder adapted to feed the articles from said receptacle, a distributor adapted to have communication with said feeder, means for operating said feeder and distributor, and a separator interposed between

said distributor and feeder and operable from the distributor.

6. In a vending machine, an article receptacle, a feeder adapted to feed the articles from said receptacle, a distributor adapted to have communication with said feeder, means for operating said feeder and distributor, and a separator interposed between said distributor and feeder and operable from the distributor and comprising arms pivoted at the opposite sides of said feeder at the delivery end thereof, lugs formed on the ends of said arms immediately adjacent to the feeder and projecting upwardly therefrom and having the upper edge thereof concaved to form a cradle, and means for supporting said arms to normal position preceding the operation of the distributor.

In testimony whereof I affix my signature in presence of two witnesses:

JULIUS NELSON CANO.

Witnesses:

FELIX HARRY MEYERS,
GEORGE HERMAN AXERHOLM.
